PROCESS OF SWEETENING PETROLEUM DISTILLATES

Minor C. K. Jones, Bound Brook, and Richard C. Brandon, Elizabeth, N. J., assignors to Standard Oil Development Company, a corporation of Delaware

Application October 29, 1941, Serial No. 416,962

8 Claims. (Cl. 196—33)

This invention relates to the art of sweetening petroleum distillates involving the dispersion of a metal sulfide, e. g., lead sulfide, in the sweetened petroleum distillate, and has the object of facilitating the separation and recovery of the metal sulfide from the sweetened distillate.

Sweetening treatments are used to improve odor, correct corrosion, and eliminate sulfur-containing compounds which have deleterious effects on the stability and combustion qualities of hydrocarbon oils. Mercaptans are the sulfur-containing impurities which are largely responsible for the need of sweetening petroleum distillates, and in a number of sweetening treatments, are reacted with salts of metals, such as lead, copper, zinc, magnesium, sodium, calcium, and the like, to yield metal sulfides which tend to remain suspended in the oils. The present invention is applicable to these treatments, particularly in so far as they form suspensions of metal sulfides which are not readily hydrolyzed and removed by washing with water.

The most common sweetening process is known as the doctor treatment. This treatment, and modifications thereof, involve the formation or use of metal sulfides which tend to remain suspended in the sweetened oil to some extent, thus requiring a water washing step and recovery of the metal sulfides from the wash water.

The doctor treatment consists in agitating a sour distillate (one containing mercaptans), with a controlled amount of sulfur and an alkaline sodium plumbite solution. The reaction results in the conversion of mercaptans to less objectionable organic disulfides and formation of lead sulfide. Most of the lead sulfide formed is separated by settling from the treated oil but some remains suspended or entrained in the sweetened oil. Accordingly, this oil is washed with water to remove the remaining suspended lead sulfide.

With the procedure of washing hitherto used, it has been impractical to satisfactorily remove the suspended lead sulfide from the sweetened oil to the extent desired due to limitations of time, apparatus, and the amount of wash water; and as a result, substantial amounts of lead sulfide left in the oil annoyingly have settled out in storage tanks. Use of wash water in extra large quantities makes recovery of the metal sulfide more difficult, because a portion of the metal sulfide tends to remain in the water phase, and results in a greater loss of lead, excessive consumption of water and power, greater loss in hydrocarbon product, and troubles from pollution

of streams or rivers by the waste water. Consequently, it is very important to improve the water washing procedure so as to obtain a more rapid separation of the lead sulfide with a restricted amount of water and apparatus.

In accordance with the present invention, certain organic substances, particularly polysaccharides, which characteristically form mucilaginous colloids with water, are used to effectively expedite the separation of lead sulfide, up to the last traces thereof, from a sweetened hydrocarbon oil in the washing step, and thereby leave a clear sweetened product.

For example, by admixing a small amount, e. g., about 0.25% by weight of starch or dextrin (starch gum) with a certain amount of wash water, the time for separation of the lead sulfide from a sweetened naphtha was shortened to about one minute and less, whereas by omitting these agents from about 25 to 50 times as much time was required for the separation.

The amount of these agents required for making a considerable increase in the separation rate is very small, being of the order of from about 0.05% to about 1% by weight of the water, and more preferably, in the range of 0.1% to 0.5%; therefore they are used in an extremely small proportion with respect to the hydrocarbon liquid treated, since only about 5% to about 30% by volume of water is used on the basis of hydrocarbon liquid treated.

The agents found to be useful in the manner described for accelerating the washing procedure vary to some extent in composition and in certain properties; hence, there is some variation in the convenience of their employment. However, they belong to recognized classes of related organic compounds. As a principal classification, these compounds are polysaccharides which are capable of being hydrolyzed to simple (mono-saccharide) sugars and are represented by the general formula $(C_6H_{10}O_5)_n$, wherein n is a large number, greater than 3.

Dextrin, which behaves very satisfactorily, is a polysaccharide formed by partial hydrolysis of starch, and it, in turn, yields glucose on hydrolysis with acids. It is soluble in water. For example, using 10% by volume of wash water containing 0.25% by weight of dextrin for washing a sweetened naphtha containing a small amount of suspended lead sulfide, following sweetening and settling, the last traces of lead sulfide were separated out by this washing in about 30 seconds, and in less than 1 minute.

Starch was used with good results. The starch

may be water-soluble, or it may be insoluble in cold water but readily swelled on heating. Starches in general were found to be effective and conveniently applied.

Agar-agar, which is another type of polysaccharide, was found effective when admixed with heated water. It is insoluble in cold water, but slowly swells and becomes soluble in hot water. By slightly acidifying the wash water, the agar-agar may be dispersed therein more readily at moderate temperatures.

In addition to the typical polysaccharides mentioned, there are numerous others which may be used but which are ordinarily less available and more expensive, e. g., gum arabic, inulin etc.

The preferred types of agents to be used for aiding the separation of the suspended metal sulfide in the washing step are those that are stable under the treating conditions and are readily dispersed homogeneously or colloidal in the wash water before or during its contact with the hydrocarbon liquid.

For the purpose of illustration, a preferred embodiment of the invention will be described with reference to a doctor sweetening process and with reference to the accompanying drawing.

In the drawing is shown a flow diagram for a continuous doctor sweetening plant in which the present process may be applied.

Referring to the drawing, a sour petroleum distillate to be sweetened is charged by inlet line 1 into mixer 2, equipped internally with orifice mixing plates 3. In this mixer the sour oil distillate is intermixed and agitated with the doctor treating solution (sodium plumbite) entering the mixer from line 4. Generally, the sour oil entering the mixer contains the desired amount of added free sulfur.

From the mixer 2, the reaction mixture is passed by line 5 to the lead sulfide settler 6, in which the lead sulfide settled to the bottom is withdrawn together with spent treating agent by line 7 for regeneration and further use.

Sweetened oil from which most of the lead sulfide has been settled, is withdrawn from settler 6 by line 10 to the water washing tower 11 equipped with wash water inlet 12, pressure control outlet 13, spent wash water drain 14, and finished oil product outlet 15.

The spent wash water is delivered by line 14 to a water settling tank 15, equipped with a bottom drain 16 for removal of water, which may be recycled to wash tower 11, an intermediate take-off line 17 for removal of water containing a concentrated suspension of metal sulfide, and skimming line 18 for removal of surface layer of oil containing very little lead sulfide.

The intermediate aqueous layer withdrawn by line 17 may be centrifuged for further concentrating the metal sulfide, which may be then subjected to regeneration.

Although the agents employed in accordance with the present invention are preferably most conveniently dissolved or dispersed in the water before it is supplied to the wash tower 11 by inlet line 12, they may be injected separately at any suitable point to facilitate settling in tower 6, or to further facilitate concentration of the metal sulfide in the water settler 15.

The use of the settling agents herein described may be practiced in various modifications of the doctor treatment. They may be used where sweetening is conducted in a batch system. They may be employed in obtaining complete separation of suspended metal sulfide when lead sulfide

is used by itself as a sweetening agent or with some other metal compound.

It is to be noted that agents which were found satisfactorily effective are substantially insoluble in the oil but have a certain amount of affinity for water. In general, they are neutral and non-ionic. Hence, they are beneficially used in obtaining a neutral finished distillate satisfactorily free of the agent and metal salts.

10 In general, the washing treatment is carried out near atmospheric pressure ranging up to about 30 lbs./sq. in. gauge and at temperatures varying from about 30° F. to 120° F.

The preferred agents have been used to obtain 15 a rapidly completed separation of metal sulfide with about half the amount of wash water ordinarily used.

A further advantage with the separation agents of the polysaccharide type is that they 20 may be used to effectively concentrate the metal sulfide in a relatively small aqueous layer between the substantially sulfide-free upper oil layer and lower body of water in a water settler so that recovery of the concentrated metal sulfide is expedited, the used wash water is in good 25 condition and easily recycled, and a good recovery of oil from the spent wash water is obtained.

It is not intended that the invention be limited to the specific examples which have been 30 given for the purpose of illustration, but it is intended that all modifications coming within the spirit of the invention be included in the scope thereof as defined in the appended claims.

We claim:

35 1. In a process of sweetening hydrocarbon distillate oils containing mercaptans involving the dispersion of metal sulfides in the sweetened distillate product, the step comprising separating said metal sulfides from the oils with the aid of an aqueous dispersion of a small amount of a polysaccharide.

2. In a process of sweetening a sour petroleum distillate by a doctor solution of alkaline sodium plumbite, the step of removing the last traces of 45 lead sulfide from the sweetened oil which comprises washing the sweetened oil with water containing a small amount of starch dispersed therein.

3. In a process of sweetening a sour petroleum distillate by a doctor solution of alkaline sodium plumbite, the step of removing final traces of 50 lead sulfide from the sweetened oil which comprises washing the sweetened oil with water containing a small amount of dextrin.

4. In a process of sweetening a sour petroleum distillate by a doctor solution of alkaline sodium plumbite, the step of removing final traces of 55 lead sulfide from the sweetened oil which comprises washing the sweetened oil with water containing a small amount of agar-agar dispersed therein.

5. In a process of sweetening a petroleum distillate containing mercaptans with a compound of a metal which forms a suspension of metal sulfide difficult to remove from the distillate by water washing, the improvement which comprises incorporating into water used the sweetening distillate about 0.05% to 1% of a polysaccharide based on the weight of the water.

6. The steps of washing out and recovering 70 final traces of suspended lead sulfide from a doctor sweetened petroleum distillate, which comprises washing said sweetened distillate with from about 5% to 30% by volume of water containing about 0.05% to about 1% by weight of a

polysaccharide which is capable of being hydrolyzed to glucose, separating spent wash water from the distillate, said spent wash water containing lead sulfide and entrained hydrocarbons, settling said spent wash water in a settling zone, wherein three layers are formed comprising a bottom body of water suitable for recycling as wash water, an intermediate aqueous layer containing suspended lead sulfide, and a top layer of hydrocarbons substantially free of lead sulfide, and separately recovering each of said layers. 10

7. In a process of sweetening a naphtha distillate containing mercaptans whereby a small amount of lead sulfide remains suspended in the sweetened distillate, the improvement of remov- 15

ing final traces of the suspended lead sulfide by washing the sweetened distillate with water containing about 0.1% to 0.5% by weight of dextrin.

8. In a process of washing a sweetened 5 naphtha distillate containing a small amount of suspended lead sulfide to remove final traces of the lead sulfide from the distillate, the improvement which comprises contacting said distillate with about 10% by volume of water containing about 0.25% by weight of dextrin, and separating from said distillate the wash water containing the removed last traces of lead sulfide within a period of about 30 seconds.
